UNITED STATES PATENT OFFICE.

HARRY J. LITT, OF SAN FRANCISCO, CALIFORNIA.

DESIGN FOR AN AUTOMOBILE-BODY.

48,664.

Specification for Design.

Patented Feb. 29, 1916.

Application filed July 27, 1915. Serial No. 42,224. Term of patent 14 years.

To all whom it may concern:

Be it known that I, HARRY J. LITT, a citizen of the United States, and a resident of the city and county of San Francisco, State of California, have invented a new, original, and ornamental Design for Automobile-Bodies, of which the following is a specification, reference being had to the accompanying drawing, forming part hereof.

Figure 1 is a side elevation of the auto-

mobile body embodying my new design. Fig. 2 is a front view of the body. Fig. 3 is a rear view of the body.

I claim:

The ornamental design for automobile body as shown.

HARRY J. LITT.
